FURNACE HAVING MULTIPLE GAS BURNERS
AND AIR DEFLECTORWilliam Russell Dalzen, Detroit, Mich., assignor
to Dalzen Tool & Manufacturing Co., Detroit,
Mich., a corporation of Michigan

Application January 23, 1946, Serial No. 642,910

1 Claim. (Cl. 158—7)

1

This invention relates to burners, and more particularly to gas burners for heating furnaces.

It is the object of the present invention to provide a novel gas burner consisting of a novel gas manifold supported upon a standard, and having a plurality of radially arranged gas outlets, a plurality of outlet pipes joined to and projecting outwardly from said outlets, and a plurality of novel burner tips carried on the ends of said pipes.

It is the object of this invention to provide a burner tip characterized by means for admitting air into a stream of gas remote from the point of combustion.

It is the further object of this invention to provide a novel cap for said burner tip which is adapted to produce a flame characterized by a plurality of combustible mixture sources.

It is the further object of this invention to provide a cap for said burner tip which will hold the flame to the outer end of said burner tip.

It is the further object of this invention to provide an air deflector plate which cooperates with the inner walls of the furnace and which has a plurality of openings corresponding to each burner tip for directing secondary air to the point of combustion of each burner tip.

It is the further object of this invention to provide a gas burner with a hollow gas manifold therefor which is positioned within a gas furnace combustion chamber, with said manifold having a plurality of gas outlets within which are positioned a plurality of spaced burner tips.

These and other objects will be seen from the following specification in conjunction with the appended drawings of which:

Fig. 1 is a partially sectioned elevational view of a furnace with gas burner positioned therein.

Fig. 2 is a top plan view of the burner.

Fig. 3 is a partially sectioned elevational view of the burner tip.

Fig. 4 is a top plan view thereof.

Fig. 5 is a bottom plan view thereof.

Fig. 6 is a partially sectioned elevational view of a slightly different form of burner.

Fig. 7 is a bottom plan view thereof.

Fig. 8 is an elevational view of a furnace showing the combustion chamber, with a slightly different type of gas burner mounted therein.

Fig. 9 is an enlarged plan view of the burner, and

Fig. 10 is a front elevational view thereof showing some of the burner tips assembled therein.

It will be understood that the above drawings

2

illustrate preferable embodiments of the invention, and that other embodiments are contemplated within the scope of the claims hereinafter set out.

Referring to Figures 1 through 7, a hot air furnace is shown in Figure 1 with outer shell 11 and inner combustion chamber housing 12 mounted on hollow cylindrical base 13, both in spaced relation to shell 11.

10 The upper part of housing 12 supports hot air radiation member 14 in communication therewith, with the products of combustion escaping therethrough and through stack opening 15. Space 16 between outer shell 11 and members 12, 15 13 and 14 provides for the upward passage of air which contacts the outer side walls of base 13, combustion chamber 12, and radiation member 14. Hot air passes upwardly into dome 17 on shell 11 and is directed as desired for heating 20 purposes through suitable ducts not shown, which are joined to said dome at outlet ports 18.

Standard 19 with support 20, is threaded into flange 21 which forms a part of hollow gas manifold 22. The latter has a gas inlet port 23 for 25 threadably receiving a suitable gas inlet pipe 23'. Said manifold also has a plurality of spaced circumferentially arranged threaded outlet ports 24, within which are threaded a plurality of gas outlet conduit pipes 25.

Said outlet pipes extend outwardly in a horizontal plane and have angular nipples 26 threaded to their outer ends. Burner tips 27 shown in detail in Figures 3, 4 and 5, have a central threaded intake opening 28; and the outer threaded ends of nipples 26 project into said openings for firmly holding the burner tips 27 in the positions and arrangement shown in Figures 1 and 2.

Referring to Figures 3, 4 and 5, burner tips 27, 40 preferably made of brass, have hexagonal outer surfaces to facilitate assembly thereof by a suitable wrench upon the ends of nipples 26. Gas intake opening 28 joins jet opening 29 in tip 27 which communicates with enlarged mixing chamber 30. A pair of oppositely arranged air inlet openings 31 are formed in burner 27 adjacent to jet opening 29, whereby the flow of gas through jet 29 and into chamber 30 has the effect of drawing in the necessary air to provide a 45 combustible mixture.

Said combustible mixture is carried through chamber 30 which converges partially at its outer end at 31', where it is ignited and where it burns continuously, as long as gas is supplied to the 50 burner tip 27.

It will be noted that the outer portion 32 of the burner tip is formed of reduced diameter to receive hollow formed burner cap 33 which is pressed thereon. Portion 32 terminates in a gradually converging end portion 34 within which are formed the four transverse auxiliary outlets 35.

Cap 33 tightly engages the reduced end 32 of burner 27; and also has an outer hollow portion of increased diameter to form the annular space 36 between the interior walls of cap 33 and the converging tip 34 of the burner.

Thus, it will be noted that an important feature of the burner tip 27 is that a combustible mixture escapes at its outer end at outlet or nozzle 31, and at the same time a portion of the combustible mixture goes into and escapes out of the end of annular chamber 36 by virtue of the transverse outlets 35.

It has been found that without said cap 33, which is also made of brass, the flame blows itself out, either by the force of the gas travelling through the burner tip 27, or by the force of the air which strikes it. On the other hand, by using cap 33 the flame is maintained at all times at the end of the burner.

Circular air deflector plate 37 has a plurality of radial slots 38 arcuately curved at 39, corresponding to each of the separate burner tips 27 which angularly project up through said slots.

Said slots terminate at their inner ends in strips 40 which form a part of plate 37.

It will be noted that said plate is supported by said strips 40 which respectively rest upon the outer walls of each of the burner tips 27. Said tips each project through slots 38 with their outer arcuate portions thereof cooperatively engaging the lower outer walls of said tips.

As illustrated in Figures 1 and 2 a plurality of secondary air openings or slots 41 are formed in plate 37 adjacent said plate strips 40, corresponding to each of the slots 38, and the burner tips 27 which project through said slots.

Triangularly pyramidal air channel members 42 are secured upon deflector plate 37 over each of the secondary air openings 41 formed therein. Secondary air from below plate 27 passes upwardly through openings 41, channel members 42, and out the triangular throats 43 thereof. Secondary air is thus an aid to complete combustion inasmuch as said air is directed to the point of combustion above each of the burner tips 27.

This has proved advantageous inasmuch as air does not pass upwardly throughout, but is directed only to the points of combustion of each burner tip where needed. While there may be a small peripheral clearance between the edges of deflector plate 37 and fire box housing 12, permitting some air to pass upwardly, still most of the air passes through throats 43 of the respective air channel members 42.

Referring to Figures 1 and 2 a suitable supply of pilot gas is provided through tube 44 which joins hollow fitting 45 extending upwardly from gas manifold 22. Pipe 46 is threaded into and supported upon the opposite side of hollow fitting 45 providing pilot gas supply to joint 47. The latter has three pilot burner pipes 48 joined thereto, each terminating in pilot burners 49, whereby three continuously burning pilot lights are provided to supply instantaneous ignition at the moment that a combustible mixture of gas and air is intermittently or otherwise supplied at burner caps 33.

The burner above described and illustrated in Figures 1 through 5 is employed particularly in converting coal or oil furnaces to gas furnaces, inasmuch as the changeover is effected merely by removing the grates or oil heating means and inserting the gas heater which is mounted upon its standard 19-20, at the same time utilizing the fire box 12-13 already available.

Referring to Figures 6, 7, 8 and 9, the same principles of invention are employed for the construction and manufacture of a gas heater. In Figure 8, a gas heater or furnace is shown with outer shell 50 and with hollow substantially square combustion chamber 51 formed by the box like housing member 52 with downwardly converging bottom portion 53. Suitable means are employed for supplying air to chamber 51; while the products of combustion rise upwardly into hollow heat exchange radiator 54. Said heat exchanger has a secondary hollow concentric chamber 55 joined thereto by passage 56. The products of combustion can then escape to a suitable stack through stack opening 57.

Air to be heated passes upwardly around combustion chamber 51-52 within the hollow portions 58 and 59, past heat exchanger 54-55, and into dome 60 for subsequent disposal for heating purposes in the conventional manner.

The gas burner element consists of the hollow rectangular gas manifold 61 which is supported within combustion chamber 51 by its gas supply pipe 62 threaded thereto, which projects through an opening in the front wall of box member 52.

A plurality of interiorly threaded openings 63 are formed within the top surface of manifold 61, for threadably receiving the exteriorly threaded lower ends 64 of the burner tips 65, illustrated in detail in Figure 6.

It will be noted that said burner tip differs from burner tip 27 in Figure 3 only in the respect that its lower end is exteriorly threaded, while in Figure 3 the lower end of the burner tip is interiorly threaded at 23. Otherwise burner tip 65 is the same as burner tip 27, and its description is not repeated.

As illustrated in Figure 9, manifold 61 consists of hollow tubular members 66 which form an approximate square, as well as the central hollow portion 67, which is joined to member 66 by the four spaced spoke like hollow member 68. So arranged, it is seen that manifold 61 with its burners 65 provides a uniform supply of heat within combustion chamber 51.

As shown in Figures 8, 9 and 10 intake pilot tube 69 has a nipple 70 at its inner end which is threaded into fitting 71. Pilot tube 72 is threadably joined in the upper end of fitting 71, and carries at its outer end a suitable pilot cap 73.

Having described my invention reference should now be had to the claim which follows for determining the scope thereof.

I claim:

In a furnace, a hollow fire box having a central opening, a gas burner having a plurality of radially spaced upwardly inclined burner tips joined to a manifold within said firebox, an air deflector plate above said manifold extending entirely across said air opening for substantial engagement with the interior walls of said firebox, having circumferentially spaced openings thru which said burner tips are projected, being removably supported upon said burner tips, also corresponding circumferentially spaced secondary openings therein arranged radially in-

wardly of said first openings, and angularly inclined outwardly flared channel members of triangular cross section positioned upon said plate inwardly of said secondary openings and extending outwardly over said secondary openings directing an air supply adjacent the ends of said burner tips.

WILLIAM RUSSELL DALZEN.
